PELT STRETCHER

Samuel Julius Falley, Rockford, Ill.

Application August 13, 1930. Serial No. 475,979

11 Claims. (Cl. 149—21)

This invention relates to a new and improved form of pelt stretcher.

The value of a pelt depends largely upon whether the same has been properly stretched, 5 because improper stretching means that only that portion of the pelt which has been properly stretched is useable, and the rest is waste material. Those engaged in this work have arrived at scales of dimensions for different kinds 10 of pelts, and a pelt that has been properly stretched and conforms to the set standard can be used practically in its entirety and can, therefore, command a much higher price than an improperly stretched pelt. Pelt stretchers have 15 been made with wedges for expansion and contraction thereof, but the objection to these stretchers has been that they expand and contract uniformly from end to end, and that is not in accordance with the accepted scale of 20 dimensions for properly stretched pelts, because in comparing a large sized pelt with a small sized pelt of a certain kind, it is found that while the body dimensions are substantially proportionately larger, so that a stretcher of the kind 25 mentioned would be suitable for that portion of the pelt, the head end of the larger pelt is not as much larger in proportion as the rest of the pelt. It is, therefore, the principal object of 30 my invention to provide a pelt stretcher of the wedge type so constructed at the head end that the expansion and contraction of that end is so graduated that a stretcher made for a certain kind of pelts will stretch a pelt of any size 35 within a given range of sizes uniformly from end to end.

More specifically stated, the stretcher of my invention has the side shaping rails hingedly or otherwise flexibly connected near the head end of the stretcher with short rail sections which 40 in turn are hingedly or otherwise flexibly connected at their outer ends. The end sections are arranged to have a certain amount of swinging movement relative to the side rails so as not to expand the head end to the same degree 45 as the rest of the stretcher as the wedge is advanced, the spread of the nose of the pelt being graduated and depending upon the distance between the outer end of the wedge and the ends 50 of the end sections.

The invention is illustrated in the accompanying drawing, in which—

Figure 1 is a face view of a pelt stretcher made in accordance with my invention;

Fig. 2 is a view on a slightly larger scale of

the one end of the stretcher showing the same in substantially fully contracted condition;

Fig. 3 is a similar view showing the same in substantially fully expanded condition, and

Fig. 4 is a cross-section on the line 4—4 of 60 Fig. 3.

The same reference numerals are applied to corresponding parts throughout the views.

The side rails 5 and 6 of the stretcher are slidably received in channel-shaped guides 7 65 mounted on the converging longitudinal edges of the wedge-shaped body member 8. The guides 7 are suitably secured by the web portions thereof to the wedge 8. The guides are preferably metallic, but the other parts may be of wood, 70 metal, fiber, or any other suitable material; wood, however, being most commonly used. Near the head end of the stretcher the side rails 5 and 6 are connected as by means of hinges 9 and 10 with end sections 11 and 12, respectively. The 75 latter are in turn hingedly connected at their outer ends, as shown at 13. While hinges are shown at 9, 10 and 13, it should be evident that any form of flexible connection may be used. For example, leaf springs could be provided to 80 form resilient flexible connections between the rails and the end sections, particularly since the angular movement of the end sections with reference to the rails is very slight, as will presently appear. The outer longitudinal edges of the rails 85 5 and 6 may be substantially straight, but the outer longitudinal edges of the sections 11 and 12 should be curved, as shown, to conform to the shape of the pelt at the head end. It will be observed that the inner ends of the sections 11 90 and 12 are cut off at an angle with reference to the outer ends of the rails 5 and 6, as indicated at 14. This allows for a predetermined amount 95 of angular movement of the end sections with reference to the side rails as appears by comparison of Figs. 2 and 3. The inner longitudinal edges of the end sections 11 and 12 are suitably cut away, as shown at 15, for clearance in the guides at the end of the wedge in the angular movement of the end sections with reference to 100 the side rails, and shoulders 16 are also provided which are arranged to come into engagement with the end of the wedge to limit the expansion of the stretcher.

In operation, it should be clear by comparison 105 of Figs. 2 and 3 that when the stretcher is contracted to its smallest size, as shown in Fig. 2, the end sections 11 and 12 provide for a certain spread of the nose of the pelt, and that when the stretcher is expanded to its full extent, as shown 110

in Fig. 3, the end sections provide for a somewhat greater spread of the nose of the pelt but not in the same proportion as the side rails 5 and 6 are expanded. The dotted lines *a* and *b* in Fig. 3 indicate what the spread would be if the parts 11 and 12 were not hinged to the parts 5 and 6, but were rigid or integral continuations thereof. It can easily be appreciated that if a pelt is properly stretched with the stretcher presenting the full line profile of Fig. 3, that this portion of the pelt would be positively ruined if stretched on a stretcher presenting the dotted line profile. The stretcher is, of course, entered in the pelt through the rear end in the usual way and the pelt contacts with the outside edges of the rails 5 and 6 and the end sections 11 and 12, thereby maintaining the proper shape. The wedge portion is used only to exert pressure to expand the side rails, and, by reason of the special construction of the stretcher as herein described, it is found that equal pressure is exerted from the nose of the pelt to the extreme rear end thereof. It is, of course, evident that stretchers of this kind can be made in different sizes for the stretching of different kinds of pelts. With my invention I am enabled to construct the stretcher so that in each position of the wedge the profile when measured at different points the length of the pelt is found to conform exactly to the scale of dimensions for different sized pelts given as a standard by those engaged in this work. If desired, the guides 7 may be provided with suitable scale markings and legends for cooperation with index marks on the side rails to facilitate adjustment of the stretcher.

The foregoing description it is believed gives a good understanding of my invention. The following claims have been drawn with a view to covering all legitimate modifications and adaptations.

I claim:

1. In a stretcher comprising an elongated body provided with forwardly converging longitudinal edges, the combination of a pair of elongated side rails alongside and slidable lengthwise of the opposite longitudinal edges of the body member, and a pair of end sections constituting continuations of the side rails, said sections being flexibly connected at one end of each to the latter and being flexibly connected to one another at the other end.

2. In a pelt stretcher, comprising a body member having forwardly converging longitudinal edges, the combination of a pair of side rails alongside and slidable lengthwise of the opposite longitudinal edges of said body member, the same having the outer longitudinal edges thereof substantially straight, and a pair of end sections having the outer longitudinal edges thereof curved and arranged in alignment with the outer longitudinal edges of the side rails, the end sections constituting continuations of the side rails, said sections being flexibly connected at the rear end thereof with the side rails and having their forward ends flexibly connected together.

3. In a stretcher of the character described comprising wedge means for expanding the stretcher, the combination of a pair of opposed elongated work engaging members directly engaged by said wedge means so as to be stretched thereby, and a pair of opposed end members also adapted to engage the work, said end members being movably connected with each other and with the other work engaging members so that

the end members are spread proportionately in the spreading of the other members but not to the same extent.

4. In a pelt stretcher comprising wedge means for expanding the stretcher, the combination of a pair of opposed elongated pelt engaging members directly engaged by the wedge means so as to be spread thereby in direct proportion to the operation of said wedge means, said members being adapted to stretch the body portion of a pelt, and a pair of opposed end members for engagement with the head portion of a pelt and movably connected with each other and with the other work engaging members so that the end members are spread proportionately in the spreading of the other members but not to the same extent.

5. In a stretcher of the character described, comprising an elongated body member, the opposite longitudinal edges of said body member converging forwardly, the combination of a side rail and an end section disposed in end to end relation at each side of the body member and slidable lengthwise of the longitudinal edges thereof, the side rails maintaining a fixed angular relation determined by the taper of the body member, and the end sections being arranged to change their angular relation depending on the position of the side rails relative to the body member, said end sections being flexibly connected with each other and with the ends of the side rails for endwise movement therewith and angular movement relative thereto, the side rails serving by frictional contact with the body member to maintain adjusted position of the side rails and end sections.

6. In a pelt stretcher comprising an elongated body member having forwardly converging longitudinal edges, the combination of side rails alongside and slidable lengthwise of the longitudinal edges of the body member, head end sections disposed end to end with the side rails with the outer longitudinal edges thereof substantially in alignment with the outer longitudinal edges of the side rails and with the ends of said sections reaching beyond the end of said body member, means providing pivotal connections between each side rail and the end section, the end sections having freedom for a certain amount of angular movement thereof relative to the side rails about the aforesaid pivots, and means providing a flexible connection between the outer ends of said sections, the side rails serving by frictional contact with the body member to maintain adjusted position of the side rails and head end sections.

7. In a pelt stretcher, comprising a body member having forwardly converging longitudinal edges, the combination of a pair of side rails alongside and slidable lengthwise of said longitudinal edges and adapted mainly for stretching the body portion of a pelt, and a separate stretching means for the head portion of the pelt, the same enclosing the small end of said body member, so that the pelt engages only it and the side rails, said means being flexibly connected with the ends of said rails to open and close as the rails are moved forwardly and rearwardly respectively, said means being constructed to remain in edge to edge alignment with the side rails in different positions of adjustment.

8. In a pelt stretcher, comprising a body member having forwardly converging longitudinal edges, the combination of a pair of side rails

- alongside and slidable lengthwise of said longitudinal edges, the outer longitudinal edges of said rails being substantially straight, and stretcher means providing a curved outline for stretching the head end of a pelt, the same enclosing the small end of said body member so that the pelt engages only said means and the side rails, said stretcher means having flexible connection with the ends of said rails in edge to edge alignment therewith. 9. In a pelt stretcher, comprising a body member having forwardly converging longitudinal edges, the combination of a pair of side rails alongside and slidable lengthwise of said longitudinal edges from a position spaced from the small end of said body member to a position extending beyond said end, separate end pieces hingedly connected with the ends of said rails for a slight amount of angular movement relative thereto, the same having clearance relative to the small end of said body member for such movement, and a hinge connection between said pieces beyond the small end of said body member. 10. A structure as set forth in claim 9 wherein at least one of said end pieces has a shoulder on the inner longitudinal edge thereof for engagement with the small end of said body member to limit the adjustment of said stretcher. 11. In a pelt stretcher, comprising a wedge member for spreading the stretcher, the combination with body stretching side rails directly engaged by the wedge member, and head stretching end members, movable means interconnecting the side rails and end members whereby the end members are simultaneously given a graduated adjustment in the adjustment of said side rails by said wedge member. 80 85 90 95 100 105 110 115 120 125 130 135 140 145 150
